UNITED STATES PATENT OFFICE

152,458

DESIGN FOR A BOOKSTAND

James Stott Dawson, New York, N. Y.

Application July 27, 1946, Serial No. 132,038

Term of patent 7 years

(Cl. D80—9)

To all whom it may concern:

Be it known that I, James Stott Dawson, a subject of the King of Great Britain, residing at New York, in the county of New York and State of New York, have invented a new, original, and ornamental Design for Bookstands, of which the following is a specification, reference being had to the accompanying drawing, forming part thereof.

In said drawing:

Figure 1 is a perspective view of the front of a bookstand, showing my new design;

Figure 2 is a perspective view of the rear of the bookstand;

Figure 3 is a top plan view on an enlarged scale;

Figure 4 is an elevation of the end of the bookstand on the same scale as Figure 3, looking in from the left of Figure 1, and

Figure 5 is an elevation of the end of the bookstand on the same scale as Figure 3, looking in from the right of Figure 1.

I claim:

The ornamental design for a bookstand, substantially as shown.

JAMES STOTT DAWSON.
